Letter Patent No. 2199 Dated Oct. 10 1865.

Design for a Trade Mark.

The schedule referred to in these letters patent and making part of the same.

Scale when it may concern:

Be it known that I, A. H. Meigs of Philadelphia, in the County of Philadelphia, and State of Pennsylvania, have invented a new and Improved Trade Mark; and I do hereby declare that the following is a full, clear and exact description thereof, which will enable others skilled in the art to make and use the same, reference being had to the accompanying drawing forming part of this specification.

My invention consists in employing for a trade mark the representation of a breast pump surrounded with appropriate reading as hereinafter specified.

The drawing clearly represents my trade mark.

In said drawing A is an engraving of a breast pump of the kind comprehended in, or described by, the trademark.

Above the pump are the words "The Improved and only Genuine Dr. Meigs Breast Pump" and below it the words "Directions, 'Apply the mouth of the glass to the breast and a finger to the small hole near the glass and gently draw the piston until the pressure is sufficient, " Will not get out of order."

My trade mark is intended to designate and describe the article for which it is intended.

I claim as my and desire to secure by letters

Patent

The design for a Trade Mark herein shown and described.

Witnesses,

George Kopfetter, John Collins.
